GRATE ACTUATING MECHANISM

George Von Haase, Lakewood, Ohio, assignor to
The American Ship Building Company, Cleve-
land, Ohio, a corporation of Ohio

Application October 20, 1939, Serial No. 300,437

9 Claims. (Cl. 110—38)

This invention relates to apparatus for feeding and burning solid fuel, and more particularly to a stoker mechanism having improved grate actuating mechanism.

Mechanical stokers have been provided heretofore of the type having two sets of reciprocable grate bars and a grate actuating mechanism operable to cause a simultaneous forward movement of the two sets of bars and independent retracting movement of such sets. However, in all of the mechanical stokers of this type with which I am aware, the grate actuating mechanism for obtaining the above-mentioned sequential actuation of the sets of grate bars has been too complex to be practical. Moreover, in the use of stoker mechanisms of this type, the various moving parts are subjected to considerable attrition due to the presence of coal dust or ashes thereon with the result that there is rapid wear and frequent adjustment or replacement of worn parts has been necessary. In view of the complexity of these prior mechanisms, such adjustment or replacement of worn parts could only be done by skilled and specially trained workmen and hence boilers equipped with such mechanisms frequently have had to remain idle until the skilled workmen could be brought to the place where the mechanism was installed.

It is, therefore, an object of the present invention to eliminate these disadvantages and to provide a mechanical stoker having improved grate actuating mechanism of an extremely simple form requiring a relatively small number of moving parts and embodying power means of a form with which power plant operators are generally familiar and on which they are capable of making adjustments and repairs whenever any become necessary.

Another object of my invention is to provide improved mechanism for actuating sets of grate bars in timed sequential relation, in which separate power devices are connected with the respective sets of grate bars and a control means common to such power devices controls the operation thereof to produce said timed sequential actuation of the sets of grate bars.

Still another object of my invention is to provide improved mechanism for actuating sets of reciprocable grate bars in timed sequential relation, in which a double-acting reciprocable fluid-pressure motor is connected with each set of grate bars so that the power strokes of the motors cause corresponding desired forward or retracting strokes or travel of the respective sets of grate bars.

A further object of my invention is to provide improved grate actuating mechanism, of the type referred to, in which each of the fluid-pressure motors has a valve and a shaft extending adjacent both motors is independently driven for actuating such valves to control the motors and thereby produce the desired timed sequential actuation of the sets of grate bars.

My invention may be further briefly summarized as consisting in certain novel combinations and arrangements of parts hereinafter described and particularly set out in the appended claims.

In the accompanying sheets of drawings,

Fig. 1 is a side elevation, with portions in section, showing a mechanical stoker embodying my improved grate actuating mechanism;

Fig. 2 is a partial front elevation showing a furnace front with my improved grate actuating mechanism thereon, this view being taken as indicated by line 2—2 of Fig. 1;

Fig. 3 is a partial plan view of the grate actuating mechanism, the same being viewed as indicated by line 3—3 of Fig. 1;

Fig. 4 is a partial side elevation showing, on a larger scale, the cams and linkage for actuating the valves of the fluid pressure motors;

Fig. 5 is a detached view of one of the valve actuating cams;

Fig. 6 is a similar view showing another valve actuating cam; and

Fig. 7 is a side elevation, partly in section, showing a modified form of my improved grate actuating mechanism.

The embodiments of my invention illustrated in the drawings will now be described more in detail, but before proceeding with the detailed description, it should be understood that my invention is not to be regarded as limited to the particular forms of apparatus and constructions herein disclosed, because it can be embodied in various other similar mechanisms and devices.

In Figs. 1 and 2 I show a support or mount having my improved grate actuating mechanism thereon and which may be in the form of the furnace front 10. The furnace front may be mounted on the outer end of the furnace or firebox 11 of a steam boiler, as indicated in Fig. 1. A plurality of grate bars 12 extend longitudinally of the furnace 11 and from the grate upon which the coal or other fuel is to be burned. The bars 12 may consist of two sets arranged with the bars 12a of one set disposed between the pairs of bars 12b of the other set. These sets of bars are supported for longitudinal reciprocating

movement in the furnace 11 so that the two sets can have simultaneous forward movement for carrying a body of fuel into the furnace and can have independent sequential retracting movement with the set of bars 12a being retracted first (while the set 12b is held) and the set 12b being retracted later. For supporting the sets of bars at their outer end and providing operating connections therewith, I may employ transversely extending rocking supports or bridge members 13a and 13b which have, along the top thereof, interengagement with the bars of the respective sets 12a and 12b.

The coal or other fuel to be burned may be supplied to the grate bars 12 by any suitable fuel feeding means, for example, I may provide a fuel hopper 14 adapted to contain a supply of coal and a fuel feeding passage 15 with which the bottom of the hopper communicates and in which a reciprocable fuel-feeding plunger 16 operates. The fuel being fed by the plunger 16 advances through the opening 17 of the furnace front and then travels down the inclined deflector 18 to the grate bars 12. The furnace front 10 may also be provided with the usual door controlled opening 19 through which fuel may be supplied to the grate by hand and through which the fire may be worked or tended. The usual ash pit opening 20 may also be provided in the furnace front for the removal of ashes from the pit beneath the grate bars 12.

For actuating the sets of grate bars 12a and 12b, I provide a pair of independent driving motors, in this instance fluid-pressure motors such as the steam engines 21a and 21b, and also provide a common control means for the engines whereby the operation thereof is controlled so as to obtain the above-mentioned desired simultaneous forward movement and independent retracting movement of the sets of grate bars. The engines 21a and 21b are preferably double-acting reciprocating engines and are connected with the respective sets of grate bars so that the power strokes of the engines will cause the desired forward and retracting movement of the sets of bars.

As shown in Figs. 1 and 2, the motors 21a and 21b may be mounted on the furnace front 10 at opposite sides of the ash pit opening 20 and preferably below the door controlled opening 19. For this purpose I may provide the furnace front with suitable brackets 22a and 22b on which the motors are mounted. For connecting the engines with their respective sets of grate bars, I may also provide on the furnace front 10 a pair of rockshafts 23a and 23b which extend transversely across the face of the furnace front in substantially axially aligned relation with each other. Suitable pairs of bearings 24a and 24b may be provided on the furnace front for supporting the rockshafts in this relation. The adjacent or inner ends of the rockshafts have depending forked arms or levers 25a and 25b mounted thereon. The arm 25a of the rock-shaft 23a may be connected with the rocking support 13a as by means of a link 26 which extends through an opening of the furnace front and has its ends pivoted, respectively, to the rocking support and the forked arm. Similarly, the arm 25b may be connected with the rocking support 13b by a link 27 which also extends through an opening of the furnace front and has its inner and outer ends pivoted, respectively, to the rocking support 13b and the forked arm 25b.

The engines 21a and 21b may be similar or

identical in construction and, therefore, only one of these engines need be described in detail. As shown in Figs. 1 and 2, the engine may be provided with a double-acting cylinder 30 having a piston 31 reciprocable therein. A piston rod 32 projects from the cylinder and at its upper or outer end is connected with a cross-head or guide 33 which is slidable on a guide rod 34 carried by the cylinder. Ports or passages 35 and 36 (see Fig. 1) connect the upper and lower ends of the cylinder 30 with a valve chest in which the piston valve 37 reciprocably operates. The valve chest may have an intermediate chamber 38 to which steam or other motive fluid under pressure may be supplied through the pipe 39 and may have exhaust chambers 40 and 41 at the ends thereof which communicate with each other and with an exhaust pipe 42 through the connecting space or passage 43. The valve 37 may have an actuating stem 44 which projects from the upper end of the valve chest.

For connecting the engine with its rock-shaft, I may provide an arm or lever 46 on the outer end of the rock-shaft and connect this arm with the cross-head 33 by means of a pair of spaced links 47. With the arrangement thus far described, it will be seen that when the piston 31 moves upwardly in the cylinder 30, it will oscillate the rock-shaft and the forked arm at the inner end thereof in a clockwise direction and outward or retracting movement will be transmitted to the set of grate bars through the link connecting the rocking support thereof with the forked arm. Downward movement of the piston in the cylinder of the engine will oscillate the rock-shaft in a counterclockwise direction and this will cause forward movement of the set of grate bars connected with the engine.

As previously stated the engines 21a and 21b are controlled so as to produce the desired sequential actuation of the sets of grate bars, and for this control function I provide valve actuating means which includes linkages 48a and 48b on the respective engines and an independently driven shaft 49 having cams 50 and 51 thereon which cooperate with the respective linkages. The valve actuating linkage 48b (the linkage 48a of the engine 21a being similar) may comprise a rocking lever 52b having one end thereof pivotally connected with the valve stem 44 and carrying at its other end a roller 53b which engages and follows the contour of the cam 51. The lever 52b may be a forked lever, or as here shown, may comprise a pair of laterally spaced links having the roller 53b therebetween. This lever is connected at an intermediate point thereof with the rock-shaft 23b by means of a depending link 54. The lower end of the link 54 is connected with the lever 52b by means of the pivot pin 55 and its upper end is eccentrically connected with the rock-shaft 23b by the eccentrically located pivot pin 56. By using the link 54 for connecting the lever 52b with the eccentric pivot pin 56 of the rock-shaft 23b it will be seen that the ability of this link to swing provides flexibility which permits the end of the lever 52b to have a straight-line movement with the valve rod 44 to which it is pivotally connected.

During the operation of the engine the lever 52b is rocked by movement imparted thereto by the cam 51 and by the link 54 and such rocking causes reciprocation of the valve 37 which controls the supply of motive fluid to the ends of the cylinder 30 and the discharge of exhaust fluid therefrom. The linkage 48b functions in a man-

ner generally similar to the reversing gear of a reciprocating engine and at times the rocking of the lever 52b is caused by the cam 51 and at other times by the eccentrically arranged link 54 and at still other times the movement of the lever 52b or the positioning thereof is the resultant effect of the movements of the cam 51 and the link 54.

As shown in the drawings the shaft 49 of the control means may be mounted for rotation on the furnace front 10 and extends transversely of the same adjacent the two engines 21a and 21b. This shaft is driven continuously during the operation of the stoker by an independent power means which, as shown in Fig. 3, may comprise a small electric motor 58 which is connected with the shaft 49 through a reduction gear 59 and a belt 60.

In the sequence of operation above indicated for the sets of grate bars, the set 12a is retracted first and may, therefore, be referred to as the leading set and the set 12b which is later retracted, may be referred to as the following set. By providing the cams 50 and 51 with the proper contour and arranging them on the shaft 49 in appropriate angular relation the engines 21a and 21b can be controlled so that the engine 21a will move first in the cycle of operation to retract the set of grate bars 12a, after which the engine 21b will move to retract the set of grate bars 12b and following this both engines will move simultaneously to advance both sets of grate bars together. By referring to Figs. 4, 5 and 6, it will be seen that the leader cam 50 has a rising section 62, a dwell section 63 and a falling section 65a. Similarly, the cam 51 has a rising section 66, a falling section 65b of identical contour with the falling section 65a of the cam 50, and a dwell section 67. With the cams mounted on the shaft 49 in the relative angular position shown in Fig. 4, it will be seen that clockwise rotation will cause a sequential operation of the valves of the two engines 21a and 21b during which the rising section 62 of the cam 50 will pass under the roller 53a of the rocking lever 52a and will lift the same to thereby cause downward movement of the valve of the engine 21a. This will permit pressure fluid to enter the lower end of the cylinder 30 and the resulting upward movement of the piston 31 will cause the set of grate bars 12a to be retracted.

The roller of the lever 52a next traverses the dwell section 63 of the cam 50 during which time the valve of the engine 21a remains in its lower position and the grate bars 12a are held in their retracted position by the pressure fluid in the lower end of the cylinder of the engine. During the time that the dwell section 63 of the cam 50 is being traversed by the roller of the lever 52a and the grate bars 12a are thus being held in their retracted position, the rising section 66 of the cam 51 passes under the roller 53b of the lever 52b causing downward movement of the valve 37 of the engine 21b. Thereupon pressure fluid is admitted to the lower end of the cylinder 30 of this engine resulting in retracting movement of the set of grate bars 12b.

Further clockwise movement of the cams 50 and 51 causes their falling sections 65a and 65b, which are of identical contour on both cams, to pass under the rollers of the levers 52a and 52b whereupon both levers will be rocked at the same time in a direction to move the valves 37 of both engines upward to admit pressure fluid to the upper ends of the cylinders. The resulting si-

multaneous downward movement of the pistons of both engines will cause the sets of grate bars 12a and 12b to be moved forward at the same time. By the time that the shaft 49 has rotated 5 through an angular distance to bring the radial line 68 under the rollers of the levers 52a and 52b, the forward movement of the sets of grate bars will have been completed. As the cams continue to rotate the rising section 62 of the cam 50 again passes under the roller of the lever 52a to lift this lever and again cause re-tracting movement of the set of grate bars 12a. During this interval, the dwell section 67 of the cam 51 passes under the roller 53b of the lever 52b and during this travel the valve of the engine 21b remains in its upper position so that pressure fluid will be maintained in the cylinder 31 above the piston resulting in the set of grate bars 12b being positively held in their forward position while the set 12a is being retracted.

As the shaft 49 continues to rotate thereafter, the engines will be operated through recurring cycles similar to that above explained and the sets of grate bars will be repeatedly reciprocated in their timed sequence. The rapidity at which these cycles of operation are carried through will depend upon the speed at which the shaft 49 is rotated and by appropriately controlling the speed of the motor 58 this can be established or varied as desired.

In further explanation of the operation of the valve linkage above described I might point out that the connection of an intermediate part of the lever 52b with the eccentric pin 56 of the rock-shaft 23b (as obtained in this instance by the link 54) provides a "follow up" movement or effect in the actuation of the valve 37 by which operation of the piston 31 is obtained at a desired slow rate and in accordance with the load or resistance imposed thereon by the set of grate bars 12b. Thus when the apparatus is started up the rock-shaft 23b is at first stationary and the clockwise rotation of the shaft 49 causes the cam section 66 to lift the lever 52b and this lever, rocking on the link 54, shifts the valve 37 downwardly to admit steam to the lower end of the cylinder. The resulting upward piston movement causes actuation of the rock-shaft which lifts the link 54 to thereby counteract more or less the movement imparted to lever 52b by the cam and cause a partial reclosing of the valve. This follow up action of the link 54 thus prevents the piston from being actuated with a sudden or slamming action.

If the set of grate bars 12b should become jammed or stuck the rock-shaft 23b will be stopped or slowed down and hence the link 54 will be less effective in following up or counteracting the movement of the lever 52b by the cam 51 and this cam will cause the valve 37 to be opened wider and wider until a sufficient steam pressure acts on the piston to overcome the stuck or jammed condition. The resulting movement of the rock-shaft and the link 54 then partially recloses the valve to prevent a subsequent too rapid action of the piston. In explaining the action of the link 54 I have referred particularly to the rock-shaft 23 and the lever 52b but it will be understood that the link 54 cooperating with the rock-shaft 23a and the lever 52a functions in a similar manner. It will be noted also that the valve 37 controls the supply of steam to one end of the cylinder and simultaneously controls the exhaust from the opposite end. Thus when the piston movement

is slowed or stopped by the above-mentioned reclosing movement resulting from the action of the link 54, the valve recloses the exhaust passage from the opposite end of the cylinder at the same time.

The rollers of the levers 52a and 52b of the valve linkages may be maintained in engagement with the cams 59 and 58 by appropriate spring pressure, or as shown in this instance, by providing the engine valves 37 with a balancing piston 69 against which steam or other pressure fluid supplied by the pipes 70 exerts a force normally tending to lift the valves.

The reciprocable fuel feeding plunger 16 above referred to, may be driven in any appropriate manner, but is preferably actuated by motion transmitted from the rock shaft 23a so that the operation of the plunger will be in timed relation to the actuation of the sets of grate bars. For this purpose I may provide an arm 71 on the rock-shaft 23 which is connected with the arm 72 of the shaft 73 by a link 74. Another arm 75 of the shaft 73 has operative connection with the reciprocable plunger 16. A lost motion connection 76 may be provided between the link 74 and the arm 72 and can be adjusted by the hand wheel 77 to thereby adjustably vary the length of stroke through which the fuel-feeding plunger 16 is actuated.

In Fig. 7 I have shown grate actuating mechanism similar to that above described, but in which a different form of connection or linkage is employed between the driving motors or engines and the rock-shafts actuated thereby. In this modified arrangement I show an engine 80 which is one of a pair of similar double-acting reciprocable fluid-pressure motors or steam engines. These engines or motors, as here shown, have a cylinder 81 in which a piston 82 is reciprocable and a piston rod 83 projecting from the cylinder carries a rack 84. A gib 85 connected with the rack 84 has slidable bearing engagement with the guide plate 86 of the guide bracket 87 for taking lateral thrust to which the rack may be subjected. A gear sector 88 carried by an arm 89, which is mounted on the rock-shaft 90, meshes with the rack 84 so that reciprocation of the piston will cause oscillation of the rock-shaft. The engine 80 embodies a valve for controlling the flow of fluid to and from the ends of the cylinder 81 and is provided with the valve linkage 91 and an actuating cam 92 similar to the linkages and cams above described for the engines 21a and 21b.

From the foregoing description and the accompanying drawings, it will now be readily seen that I have provided a mechanical stoker having improved grate actuating mechanism of simplified form and embodying a minimum number of moving parts. It will be seen furthermore that in my improved grate actuating mechanism I employ a separate engine or power device for each set of grate bars and provide an independently driven common control means for the engines whereby they operate in a cycle to produce a desired simultaneous forward movement and independent retracting movement of the sets of grate bars. It will also be seen that by providing a double-acting reciprocable engine for each set of grate bars, a direct actuation of the sets of bars can be obtained in accordance with the power strokes of the engines. It will be further seen that in providing the independent engines for actuating the sets of grate bars, as above explained, the power means of the

mechanism will be of a type with which power plant operators are generally familiar and on which repairs and adjustments can be made by them thus avoiding the delay and expense which would otherwise be encountered in calling upon skilled technicians or engineers for the making of such repairs or adjustments.

While I have illustrated and described my stoker and improved grate actuating mechanism in a more or less detailed manner, it should be understood that I do not wish to be limited to the precise construction and arrangements herein disclosed but regard my invention as including such changes and modifications as do not constitute a departure from the spirit of the invention and the scope of the appended claims.

Having thus described my invention I claim:

1. In apparatus of the character described, a support, a plurality of sets of movable grate elements, rock-shafts journaled on said support and connected with the respective sets of grate elements, fluid-pressure motors mounted on said support and connected with the respective rock-shafts, a valve for each motor, and means for timing the actuation of said valves including a separate power device and a shaft driven thereby and having a cam thereon adjacent each motor.

2. In apparatus of the character described, a support, a pair of sets of movable grate elements, 30 a pair of rock-shafts journaled on said support in substantially aligned relation, means connecting the adjacent ends of said shafts with the respective sets of grate elements, a pair of double-acting reciprocating fluid-pressure motors mounted on said support and connected with the respective rock-shafts adjacent their outer ends, each of said motors including a valve, a shaft mounted on said support to extend adjacent both of said motors, independent power means for driving the last-mentioned shaft, and cams on said last-mentioned shaft for causing timed actuation of the valves of said motors.

3. In apparatus of the character described, a pair of sets of reciprocable grate elements arranged for simultaneous movement through a forward stroke and independent movement through their retracting stroke, a pair of double-acting fluid-pressure cylinders having reciprocating pistons connected with the respective sets of grate elements so that a power stroke of each piston causes the corresponding set of grate elements to be moved through its stroke, a valve for each cylinder, a shaft extending adjacent both cylinders, means for continuously and independently driving said shaft during the operation of the apparatus, and cams on said shaft for actuating said valves in timed sequence to cause said simultaneous forward movement and independent retracting movement of said sets of elements.

4. In apparatus of the character described, a pair of sets of reciprocable grate elements arranged for simultaneous movement through a forward stroke and independent movement through their retracting stroke, a pair of double-acting fluid-pressure cylinders having reciprocating pistons connected with the respective sets of grate elements so that a power stroke of each piston causes the corresponding set of grate elements to be moved through its stroke, a valve for each cylinder, a shaft extending adjacent both cylinders, independent power means for driving said shaft, cams on said shaft adjacent the respective cylinders, and means actuated in part 60 by said cams and partially by the movement of

said pistons for shifting said valves to control the operation of said cylinders.

5. In apparatus of the character described, a support, a pair of sets of movable grate elements, a pair of rock-shafts journaled on said support in substantially aligned relation, means connecting the adjacent ends of said shafts with the respective sets of grate elements, a pair of double-acting reciprocating fluid-pressure motors mounted on said support and connected with the respective rock-shafts adjacent their outer ends, each of said motors including a valve, a shaft mounted on said support to extend adjacent both of said motors, independent power means for driving the last-mentioned shaft, 10 cams on said last-mentioned shaft adjacent the respective motors, valve operating levers arranged to receive movement from said cams, and means whereby said rock-shafts impart movement to said valve operating levers so as to at least partially counteract the movement received from said cams.

6. In apparatus of the character described, a support, a pair of sets of movable grate elements, a pair of rock-shafts journaled on said support in substantially aligned relation, means connecting the adjacent ends of said shafts with the respective sets of grate elements, a pair of double-acting reciprocating fluid-pressure motors mounted on said support and connected with the respective rock-shafts adjacent their outer ends, each of said motors including a valve, a shaft mounted on said support to extend adjacent both of said motors, independent power means for driving the last-mentioned shaft, 15 cams on said last-mentioned shaft adjacent the respective motors, valve operating levers arranged to receive movement from said cams, and means whereby said rock-shafts impart movement to said valve operating levers so as to at least partially counteract the movement received from said cams.

7. In apparatus of the character described, a

supporting structure having an upright front wall, a grate extending forwardly away from said front wall and comprising a pair of sets of movable grate bars adapted to support a fuel bed, said sets being arranged for substantially simultaneous forward movement for advancing the fuel bed and an independent retracting movement, a pair of rock-shafts journaled on said front wall and extending in a direction transversely thereof, means connecting the shafts with the respective sets of grate bars for transmitting motion thereto, a pair of double-acting fluid-pressure cylinders mounted on said upright wall and having reciprocating pistons connected with the respective rock-shafts so that a power stroke of each piston causes the corresponding set of grate bars to be moved through its travel, control valves adjacent the cylinders and adapted to be actuated in timed relation such that said pistons produce said simultaneous forward and said independent retracting movement of said sets of grate bars, and means for causing such timed actuation of the valves

including a common valve-actuating shaft extending transversely of said upright wall and a continuously operating power device connected with said valve-actuating shaft.

8. In apparatus of the character described, a supporting structure having an upright front wall provided with a fire-tending opening, a grate extending forwardly away from said front wall and comprising a pair of sets of movable grate bars adapted to support a fuel bed, said sets being arranged for substantially simultaneous forward movement for advancing the fuel bed and an independent retracting movement, a pair of rock-shafts journaled on said front wall and extending transversely thereof in substantially axially aligned relation, means connecting the adjacent inner ends of the shafts with the respective sets of grate bars for transmitting motion thereto, a pair of double-acting fluid-pressure cylinders mounted on said upright wall on opposite sides of said fire-tending opening and having reciprocating pistons connected with the outer ends of the respective rock-shafts so that a power stroke of each piston causes the corresponding set of grate bars to be moved through its travel, control valves adjacent the cylinders and adapted to be actuated in timed relation such that said pistons produce said simultaneous forward and said independent retracting movement of said sets of grate bars, and means for causing such timed actuation of the valves including a common valve-actuating shaft extending transversely of said upright wall and a continuously operating power device connected with said valve-actuating shaft.

9. In apparatus of the character described, a supporting structure having an upright front wall, a grate extending forwardly away from said front wall and comprising a pair of sets of movable grate bars adapted to support a fuel bed, said sets being arranged for substantially simultaneous forward movement for advancing the fuel bed and an independent retracting movement, a pair of rock-shafts journaled on said front wall and extending in a direction transversely thereof, means connecting the shafts with the respective sets of grate bars for transmitting motion thereto, a pair of double-acting fluid-pressure cylinders mounted on said upright wall and having reciprocating pistons connected with the respective rock-shafts so that a power stroke of each piston causes the corresponding set of grate bars to be moved through its travel, control valves adjacent the cylinders and adapted to be actuated in timed relation such that said pistons produce said simultaneous forward and said independent retracting movement of said sets of grate bars, a valve shaft extending transversely of said upright wall and carrying valve-actuating cams, and a continuously operating power device connected with said valve shaft, the contour of said cams being such that the valve for one cylinder will be actuated to maintain fluid-pressure in such cylinder for holding the corresponding set of grate bars stationary while the other set is being retracted by its cylinder.
